(57) **CLAIM**

The ornamental design for a shingle, as shown and described.

DESCRIPTION

FIG. 1 is a top plan view of a shingle showing a first embodiment of my new design;

FIG. 2 is a top plan view of a second embodiment of my design;

FIG. 3 is a top plan view of a third embodiment of my design;

FIG. 4 is a top plan view of a fourth embodiment of my design;

FIG. 5 is a top plan view of a fifth embodiment of my design;

FIG. 6 is a top plan view of a sixth embodiment of my design;

FIG. 7 is a top plan view of a seventh embodiment of my design;

FIG. 8 is a top plan view of an eighth embodiment of my design;

FIG. 9 is a top plan view of a ninth embodiment of my design;

FIG. 10 is a top plan view of a tenth embodiment of my design;

FIG. 11 is a top plan view of an eleventh embodiment of my design;

FIG. 12 is a top plan view of a twelfth embodiment of my design;

FIG. 13 is a top plan view of a thirteenth embodiment of my design;

FIG. 14 is a top plan view of a fourteenth embodiment of my design;

FIG. 15 is a right side view of all embodiments of FIGS. 1-14;

FIG. 16 is a front elevation view of an embodiment of FIG. 1;

FIG. 17 is a front elevation view of an embodiment of FIG. 2;

FIG. 18 is a front elevation view of an embodiment of FIG. 3;

FIG. 19 is a front elevation view of an embodiment of FIG. 4;

FIG. 20 is a front elevation view of an embodiment of FIG. 5;

FIG. 21 is a front elevation view of an embodiment of FIG. 6;

FIG. 22 is a front elevation view of an embodiment of FIG. 7;

FIG. 23 is a front elevation view of an embodiment of FIG. 8;

FIG. 24 is a front elevation view of an embodiment of FIG. 9;

FIG. 25 is a front elevation view of an embodiment of FIG. 10;

FIG. 26 is a front elevation view of an embodiment of FIG. 11;

FIG. 27 is a front elevation view of an embodiment of FIG. 12;

FIG. 28 is a front elevation view of an embodiment of FIG. 13;

FIG. 29 is a front elevation view of an embodiment of FIG. 14;

FIG. 30 is a rear elevation view of all the embodiments of FIGS. 1-14; and,

FIG. 31 is a bottom plan view of all the embodiments of FIGS. 1-14.
